COMBINED HANDLE AND LATCH FOR CABINET
DRAWERS, DOORS, AND THE LIKE

Herbert S. Fall, Indianapolis, Ind.

Application May 14, 1957, Serial No. 46,167

Term of patent 14 years

(Cl. D10—8)

Fig. 1 is a front elevational view of a combined handle and latch for cabinet drawers, doors, and the like showing my new design.

Fig. 2 is a side elevational view of the combined handle and latch for cabinet drawers, doors, and the like.

Fig. 3 is a rear elevational view of the combined handle and latch for cabinet drawers, doors, and the like.

Fig. 4 is an elevational view of the side opposite from that as shown in Fig. 2.

I claim:

The ornamental design for a combined handle and latch for cabinet drawers, doors, and the like, as shown.
